(57) **CLAIM**

The ornamental design for a jewelry and scarf organizer, as shown and described.

DESCRIPTION

FIG. 1 is a front elevational view of an embodiment of the present invention, a jewelry and scarf organizer, showing pockets for also holding footwear or shoes;

FIG. 2 is a rear elevational view thereof;

FIG. 3 is a right side elevational view thereof;

FIG. 4 is a left side elevational view thereof;

FIG. 5 is top plan view thereof; and,

FIG. 6 is a bottom plan view.

The broken lines shown in the drawings and FIGS. are included for the purpose of illustrating the environmental structure and form no part of the claimed design.
